UNITED STATES PATENT OFFICE.

SIMON GOLDNER, OF NEW YORK, N. Y.

DESIGN FOR A FINGER-RING.

SPECIFICATION forming part of Design No. 33,725, dated December 18, 1900.

Application filed November 21, 1900. Serial No. 37,293. Term of patent 7 years.

To all whom it may concern:

Be it known that I, SIMON GOLDNER, a citizen of the United States, residing in the borough of Manhattan, in the city, county, and State of New York, have invented and produced a new and original Design for Finger-Rings, of which the following is a specification.

This design consists in a Tiffany finger-ring having a figure of a coiled snake at each side of the setting portion of the ring.

The design is illustrated in the annexed drawings, in which—

Figure 1 is a front elevation of the ring. Fig. 2 is a side elevation of Fig. 1. Fig. 3 is a plan view of Fig. 1.

The ring is shown at 1, having the setting portion at 2. This setting portion 2, of suitable form, looks like a crown. At each side of the setting is a figure 3, representing a snake coiled about the ring. The heads of the snakes look toward the setting and give

the appearance to the latter of being held or gripped by the mouths of the snakes. Looking down onto the setting the snakes appear coiled in opposite directions, so that when the ring is held to look at the setting first from one side and then from the other each snake appears to coil from its tail toward the setting in one direction—say to the right.

The design gives a striking and characteristic appearance.

What I claim as new, and desire to secure by Letters Patent, is—

The design for a finger-ring as herein shown and described.

In testimony whereof I have hereunto set my hand in the presence of two subscribing witnesses.

SIMON GOLDNER.
